UNITED STATES PATENT OFFICE

138,088

DESIGN FOR AN ARTIFICIAL FISH BAIT

Ray R. Moblo and Myrtle Moblo,
Bellingham, Wash.

Application November 30, 1943, Serial No. 111,830

Term of patent 14 years

(Cl. D31—4)

To all whom it may concern:

Be it known that we, Ray R. Moblo and Myrtle Moblo, both citizens of the United States, residing at Bellingham, in the county of Whatcom and State of Washington, have invented a new, original, and ornamental Design for Artificial Fish Bait, of which the following is a specification, reference being had to the accompanying drawing, forming part thereof.

Figure 1 is a top plan view of an artificial fish bait showing our new design, and
Figure 2 is an edge view thereof.

We claim:

The ornamental design for an artificial fish bait, as shown.

RAY R. MOBLO.
MYRTLE MOBLO.
